US0D1101768S

(12) **United States Design Patent** (10) **Patent No.:** **US D1,101,768 S**
Buchanan et al. (45) **Date of Patent:** **** Nov. 11, 2025**

(54) **COMBINED ELECTRONIC DEVICE AND DISPLAY SCREEN OR PORTION THEREOF WITH GRAPHICAL USER INTERFACE**

(71) Applicant: **Visa International Service Association**, San Francisco, CA (US)

(72) Inventors: **Andrew Buchanan**, Marylebone (GB); **Hollie Dee Thistlewood**, Marylebone (GB)

(73) Assignee: **Visa International Service Association**, San Francisco, CA (US)

(**) Term: **15 Years**

(21) Appl. No.: **29/875,731**

(22) Filed: **May 9, 2023**

Related U.S. Application Data

(62) Division of application No. 29/710,794, filed on Oct. 25, 2019, now Pat. No. Des. 988,335.

CLAIM

The ornamental design for a combined electronic device and display screen or portion thereof with graphical user interface as shown and described.

DESCRIPTION

FIG. 1 shows a perspective view of a combined electronic device and display screen or portion thereof with graphical user interface showing our new design;
 FIG. 2 shows a front view thereof;
 FIG. 3 shows a back view thereof;
 FIG. 4 shows a right side elevational view thereof;
 FIG. 5 shows a left side elevational view thereof;
 FIG. 6 shows a bottom elevational view thereof; and,
 FIG. 7 shows a top elevational view thereof.

1 Claim, 4 Drawing Sheets
